Des. 242,421
Patented Nov. 23, 1976

242,421

MICROWAVE OVEN

Martin H. Pitstick, Cleves, Ohio, and Charles H. Schmitt,
Louisville, Ky., assignors to General Electric Company

Filed May 12, 1975, Ser. No. 576,800

Term of patent 14 years

Int. Cl. D7—02

U.S. Cl. D7—128

FIG. 1

FIG.2

FIG.3

FIG. 1 is a perspective view of a microwave oven showing our design;

FIG. 2 is a top plan view thereof; and

FIG. 3 is a side elevational view thereof.

The side of the oven which is not shown is a mirror image of the side disclosed in FIG. 3. The bottom surface of the oven is substantially plain and unornamented.

We claim:

The ornamental design for a microwave oven, as shown and described.
